(57) **CLAIM**

We claim the ornamental design for a protective sports helmet, as shown and described.

DESCRIPTION

FIG. 1 is a perspective view of a protective sports helmet; FIG. 2 is a front view of the protective sports helmet; FIG. 3 is a side view of the protective sports helmet; FIG. 4 is a top view of the protective sports helmet; FIG. 5 is a rear view of the protective sports helmet; and, FIG. 6 is a bottom view of the protective sports helmet. The broken lines which represent boundary lines and unclaimed details form no part of the claimed design.
